RIVET SQUEEZER AND THE LIKE

Peter F. Rossmann, Snyder, N. Y.

Application June 30, 1942, Serial No. 449,191

4 Claims. (Cl. 78—42)

The present invention relates generally to machines or devices of the type embodying relatively reciprocating members for applying pressure to work positioned between said members, more particularly to a rivet squeezer, but equally useful for punching, pressing, forging and similar operations.

An object of the invention is to provide a rivet squeezer or the like constructed and arranged to deliver a maximum pressure at any point of the working stroke or travel of its relatively reciprocable rivet sets or equivalent pressure applying members.

Another object is to provide a rivet squeezer or the like which, while of small size and of low weight, will enable a substantial pressure to be applied to the work, thereby greatly increasing its flexibility in use and allowing of manual or direct hand operation.

A further object is to provide a rivet squeezer or the like capable of enabling an accurate control of the extent of travel of its relatively movable or pressure applying member by the operator, in particular to stop the pressure application at any point of the working stroke of the device to suit existing requirements and operating conditions.

These and further objects of the invention will be in part discussed and in part become apparent from the following detailed description of two practical embodiments thereof taken with reference to the accompanying drawings forming part of this specification and wherein:

Figure 1 is a longitudinal cross-sectional view of a rivet squeezer, in the normal or non-use position, embodying the principles of the invention; Figure 2 is a section taken on line 2—2 of Figure 1; Figure 3 is a section taken on line 3—3 of Figure 1; Figure 4 is a partial top view of Figure 1; Figure 5 is a fragmental view of Figure 1 showing the position at an intermediate point during the working stroke; Figure 6 is a longitudinal cross sectional view of a rivet squeezer similar to Figure 1 and embodying a modification of the invention; Figure 7 is a view similar to Figure 6 being in part in elevation and showing the position at an intermediate point of the operating stroke; Figure 8 is a section taken on line 8—8 of Figure 6; Figure 9 is a section taken on line 9—9 of Figure 6; and Figure 10 is a plot showing the working pressure obtained during the operating stroke with a device according to the invention compared with known rivet squeezers at present in commercial use.

Like reference characters identify like parts throughout the different views of the drawings.

Referring to the embodiment of the invention shown in Figures 1 to 4, the numeral 10 indicates a cylindrical housing of my improved rivet squeezer having an integral end wall 11 at its front and being provided with a screwed-on or otherwise secured cover or cap 12 at its rear, said cap having an integral cylindrical extension or sleeve 13 of lesser diameter than and coaxial with the housing 10.

The movable unit of the squeezer comprises a hollow shaft 14 carrying an anvil or rivet set 15 at its front end and serving to support a plurality—four being shown in the drawings—of disc-shaped pistons 16 preferably equally spaced from each other and supported by the inner casting wall in such a manner that the entire assembly comprising said shaft and pistons is free to move axially. In the example illustrated, the pistons 16 having an inner diameter to afford an easy slip-fit over the shaft 14 are secured to the latter by means of ring-shaped spacers 17 and a nut 18 engaging the threaded end of the rear portion 20 of reduced thickness of the shaft 14 and screwed tightly against the edge of the rearward-most spacer 17 with the forward-most piston 16 engaging a flange or stop 21 of the shaft 14 to result in a rigid shaft-piston assembly 14, 16, 17, 18.

The stationary or immovable unit of the squeezer comprises a plurality of annular spacing discs or separating walls 23 secured to the inside wall of the housing 10 by means of outer spacer rings 24 similar to the spacers 17 and clamped between the outer edges of the discs 23 by the cap 12 gripping the rearward-most disc 23 with the forward-most spacer engaging the front wall 11 of the housing 10. The inner edges of the discs are fitted with suitable packings 25 retained by packing rings 26 which are connected by rivets 27 or otherwise secured to the discs to provide an airtight, slidable connection with the spacer rings 17 of the movable unit. Similarly, the outer edges of the pistons 16 are fitted with packings 28 retained by packing rings 30 which are connected by rivets 32 or otherwise secured to the pistons to provide an air-tight sliding engagement with the outer stationary spacer rings 24. There are thus provided a plurality of high and static pressure chambers to the right and left of each piston indicated by the letters S and H, respectively, in the drawings.

The static pressure chambers S are constantly connected with the outside atmosphere through

suitable portholes 33 passing through the spacer rings 24 and the outer wall of housing 10. Moreover, inlet openings 34 or portholes are provided from the inside of shaft 14 to the high pressure chambers H passing through the wall of said shaft and the spacing rings 17. As more clearly shown in Figures 2 and 3, the spacing rings 17 and 24 are provided with annular grooves 34' and 33', respectively, registering with an communicating with the adjacent portholes whereby the ingress and egress of compressed air or other medium is insured in any relative position of said rings with respect to the shaft 14 and housing 10, respectively.

There is further provided in Figure 1 a cooperating anvil or rivet set 35 disposed opposite to the anvil 15 and adjustably mounted in the free end of a removable yoke screwed on or otherwise detachably secured to a threaded extension sleeve 37 of the housing 10, said sleeve acting as a bearing for the anvil 15. Any other type of pressure applicator may be provided depending on the use and purpose for which the squeezer is designed as will be readily understood.

In order to move the entire piston assembly comprising parts 14, 16, 17, 18 and to apply pressure to the work such as a rivet placed between the anvil 15 and the cooperating anvil or rivet set 35, there is provided an adjustable valve structure for admitting compressed air, liquid or an equivalent medium into the high pressure chambers H, said valve being designed in such a manner as to synchronize the movement of the valve adjusting element controlled by the operator with the advance or travel of the pistons so as to enable an accurate control of the speed and movement of anvil 15 and in turn of the degree and period of pressure application to the work being operated on within the operating range or working stroke of the squeezer.

In order to normally maintain the squeezer in the zero or starting position shown in Figure 1, there is provided in the example shown a coiled compression spring 48 arranged within shaft 14, the rear end of said spring engaging a plug 40 screwed into the end of the rear shaft portion 20 to form an air or liquid-tight closure and the front end of said spring bearing against the rear end of a cylindrical plug 41 placed inside the shaft 14 and having its front end engaging the inside of anvil 15. Plug 41 which snugly fits within the shaft 14 is retained against rotation by means of a pin 42 mounted in press-fit engagement within a bore through the extension 37 of the housing. Shaft 14 is further provided with a slot 43 engaged by pin 42 to enable axial movement of the shaft within a given range or stroke for which the device is designed. The plug 41 is furthermore of sufficient length to act as a seal for and prevent compressed air within shaft 14 from entering the forward-most static pressure chamber.

The control and valve mechanism comprises a cylindrical, suitably knurled or fluted hand grip 44 rotatably mounted upon the extension sleeve 13 of the housing 10 and a cylindrical valve member 45 in snug fitting and rotating engagement with the inside of sleeve 13. Said valve member has an inner diameter somewhat larger than the diameter of the adjacent shaft portion 20 and is provided with an inwardly directed annular flange or rim 46 engaging the outer surface of shaft portion 20 and serving as a valve element cooperating with the inlet portholes 47 through said shaft in the manner to be described

presently. Valve member 45 is normally urged into its rearward-most or zero position by any suitable means consisting in the example shown, of a coiled compression spring 48 encircling the rearward-most spacing ring 17 with one end engaging the rearward-most separating disc 23 and with its other end bearing against a shoulder of the member 45.

Valve member 45 is connected with the hand grip 44 through a pin or set screw 50 having an intermediate portion arranged to move within an oblique guide slot 51 in the sleeve 13 (see Figure 4), whereby rotation of hand grip 44 will result in an axial forward movement of the valve member 45. A flexible tube 52 from a supply tank of compressed air or the like (not shown) is screwed into the rear end of the sleeve 13, the arrow A in the drawings indicating the direction of entrance of the compressed air or other medium.

The function and operation of the rivet squeezer aforescribed is as follows: In the zero or rest position shown in Figure 1, both the static and high pressure chambers S and H are connected to the outside atmosphere directly through the portholes 33 on the one hand and through portholes 34 by way of the inside of shaft 14, valve portholes 47 and exhaust portholes 53 on the other hand, respectively. In this position, the compressed air supply as indicated by the arrow A is blocked by the valve element 46 which closely engages the outer surface of rear shaft portion 20. If now the hand grip 44 is rotated in the clockwise direction, the valve member 45 will advance axially in the forward direction against the action of the spring 48 due to the pin 45 sliding within the guide slot 51 in the manner described. As a result, the valve element 46 will at first cover the portholes 47 thereby shutting off the high pressure chambers H from the outside air. Further advance of the valve by continued rotation of the hand grip 44 will result in the uncovering of the valve ports 47 as shown in Figure 5 and admission of compressed air or other medium. Accordingly therefore the compressed air will enter the inside of shaft 14 and pass through ingress portholes 34 into the high pressure chambers H, the path of the air being indicated by the dotted arrows in Figure 5. All the pistons 16 will thus be simultaneously moved in the forward direction, resulting in a corresponding advance of the anvil or rivet set 15 and application of pressure to the work such as a rivet placed therebetween and the cooperating anvil 35. The position of anvil 15 at the end of the working stroke has been indicated in dashed lines in Figure 1.

The employment of a plurality of simultaneously operated pistons in tandem arrangement as shown has the effect of a correspondingly increased total pressure applied by the anvil 15 and results in a highly compact rivet squeezer of considerably reduced size and weight suitable for hand operation even for comparatively large size rivets or working pressures.

The initial movement of the piston 16 as a result of the rotation of the hand grip 44 to a certain extent in the manner described, in its turn will entail an axial forward movement of the shaft 14, 20 which forms a rigid unit together with the pistons, whereby after a certain advance of the pistons determined by the initial extent of rotation of the hand grip, the valve will be returned to its relative initial position, where-in the valve element 46 will again register with

the valve portholes 47, thereby shutting off the air supply. In order to cause continued piston movement, it will be necessary to continue or follow up with the hand grip movement to reopen the air inlet valve. From this it is seen that the travel or advance of the pistons 16 and the anvil 15 may be accurately timed and regulated at the discretion of the operator or in other words synchronized with the valve control within the limits determined by the extreme valve positions or working stroke of the device. In this manner, by a follow up control of this type, the speed of travel during the complete power stroke, the length of the stroke and degree of pressure application may be controlled and individually adjusted to suit existing requirements and conditions.

Upon release of the hand grip either at the end of the operating stroke or at any intermediate point thereof, the valve will be returned to its zero or starting position by the spring 48 as shown in Figure 1, whereby the inside of the shaft will be connected with the outside atmosphere, allowing the compressed air in the pressure chambers H to escape through portholes 34, shaft 15, valve portholes 47 and exhaust portholes 53. At the same time, the spring 38 will return the entire movable unit to its rearward-most or starting position as shown in Figure 1.

From the foregoing it will be understood that the tandem arrangement of a plurality of pistons simultaneously operated by a suitable compressed medium may be used in connection with any other known type of valve and control device and that the synchronized or follow-up control of the piston travel or pressure application is not limited to the use of more than one piston but may be employed in combination with any type of piston without departing from the scope and spirit of the invention.

Referring to Figures 6 to 9, there is shown a modified power squeezer differing from the construction of Figure 1 by the elimination of the return spring 38 and provision of means to return to and maintain the movable unit in its zero position by pneumatic pressure. The housing 10, separating discs 23, the movable unit comprising pistons 16 and shaft 14 as well as the operating parts 44, 45, and 50 of the valve structure are substantially similar to those according to Figures 1 to 5 with the exception that the outer portholes 33 are omitted and one or more pistons, in the example shown the rearward-most piston 16', are arranged for operation by air pressure in either direction. Accordingly therefore the chambers Hs and Sh on the opposite sides of piston 16' are utilized both as high and static pressure chambers to cause piston 16' to act simultaneously with the remaining pistons during the forward or power stroke and to serve as a means for returning the movable unit of the squeezer to and normally maintaining it in its rearward-most or zero position. In other words, piston 16' serves both as an operating piston together with the remaining pistons 16 during the forward travel in the same manner as in the case of Figure 1 and is utilized additionally as a means to return and urge the movable unit into its zero position; that is, taking the place of the coiled spring 38 of Figure 1.

For the aforementioned purpose, there is provided in the embodiment according to Figures 6 to 9 a modified valve structure designed in such a manner that normally, i. e., in the zero position of the squeezer shown in Figure 6, the high pres-

sure chambers H are disconnected from the compressed air supply with the exception of chamber Hs to the left of the return piston 16' in such a manner that the movable unit will be urged to and maintained in the rearward-most or zero position. At the same time, the static pressure chambers S and the chamber Sh to the right of the return piston 16' are connected with the outside atmosphere. Upon rotation of the hand grip or other control element, the valve will assume a position so as to admit compressed air into the high pressure chambers H in a manner similar to that according to Figures 1 to 5, while at the same time the relationship between chambers Hs and Sh on both sides of the return piston 16' will be reversed, i. e., chamber Hs will become a static pressure chamber connected to the outside atmosphere similar to the chambers S, while chamber Sh will become a high pressure chamber connected to the compressed air supply similar to the chambers H. The valve is advantageously so constructed that at first the change from static to high pressure and vice versa in the chambers Sh and Hs will be effected, whereupon the compressed air will be admitted to all the high pressure chambers for initiating the power stroke and effecting the advance of the anvil or other pressure applicator.

Upon release of the hand grip at a point within or at the end of the working stroke, the valve will be returned to its zero position in a manner similar to that according to Figures 1 to 5, reversing thereby the above operations, i. e., allowing the air in the high pressure chambers to escape to the outside and re-establishing the original relationship between the chambers Hs and Sh so as to result in a return of the device to its zero or starting position.

The aforescribed operation is effected according to the construction shown in Figures 6 to 9 by means of a modified valve structure comprising a first tube 55 snugly fitting and slidably within the shaft 14, said tube containing two separate longitudinal chambers s and h such as, in the embodiment shown, by the provision of a further tube 56 of lesser diameter brazed to or otherwise secured to the inside of tube 55 as shown more clearly at 57 in Figures 8 and 9. Chamber h is permanently under high pressure by direct connection to the high pressure intake valve chamber Vh, and tubular chamber s having its opposite ends hermetically closed by means of plugs 60 and 61 is connected to the outside or static pressure through the exhaust portholes 62 at the rear end of tubes 55 and 56 communicating with the static pressure valve chamber Vs which in turn communicates with the outside atmosphere through the exhaust portholes 53.

The high and static pressure valve chambers Vh and Vs are separated by the inner flange or rim 63 of valve member 45 rigidly secured in an airtight manner such as by shrinking or the like to the projecting right end of valve tube 55. As a result, rotation of the hand grip 44 will cause both valve tubes 55 and 56 to axially move within the shaft 15, 20 in the forward direction, thereby closing and opening the several air ingress and egress portholes through the members 14, 17 and 56 between the static pressure and high pressure chambers s and h on the one hand and the piston chambers S, H, Sh, Hs on the other hand in a manner similar to that described hereinbefore.

The relative arrangement of the annular groove in the members 17 and 55 and cooperat-

ing portholes through the members 55, 14, 17 and 56, 55, 14 and 17, respectively, is such that in the zero position as shown in Figure 6, all the chambers S as well as chamber S_H are at static pressure being connected to chamber s, while chamber H_s is connected to the high pressure chamber h, thereby urging the entire movable unit into its rearward-most or zero position.

If the hand grip 44 is now rotated in a clockwise direction to a certain extent as shown in Figure 7, at first the relationship between chambers H_s and S_H is reversed, i. e., chamber H_s is connected to chamber s thus allowing the compressed air therein to escape to the outside, while chamber S_H is connected to chamber h together with the other high pressure chambers H resulting in a subsequent advance of the pistons. The advance of the pistons in turn entails a forward movement of the shaft 14 until restoring the original relative valve position and interrupting the compressed air supply. Continued rotation of the hand grip will result in a corresponding advance or follow-up of the pistons in substantially the same manner as described in connection with Figure 1. If the hand grip is released, the relative movement of the valve tubes 55 and 56 with respect to the shaft 14 will be reversed by the return spring 48 urging the valve back into its zero or rearward-most position. During this return movement the chambers H are temporarily connected with the chamber s thereby allowing the air in the high pressure chambers to escape to the outside, whereupon at the end of the valve return movement chamber H_s will be connected to chamber h and chamber S_H will be connected to chamber s, resulting in a return of the entire movable unit to its rearward-most or zero position in the manner understood from the foregoing.

Due to the use of piston 16' as an operating element both during the forward travel and for effecting the return of the pistons to the zero position, the chamber enclosed by the two rearward-most separating discs 23 and 23' has to be increased accordingly depending on the extent of the travel or operating stroke, and the piston 16' as well as disc 23' are fitted with suitable packings on either side thereof by reason of the fact that air pressure is applied to both sides of these members.

An advantage of a squeezer according to the invention, in addition to the accurate and gradual control of the travel or operating stroke in the manner described, is the fact that the desired pressure is directly applied from the pistons to the pressure-applying member or anvil by the use of a suitable number of pistons in tandem substantially without any intermediate linkage or like power transmission mechanisms as used in the prior art devices in order to obtain a desired working pressure. In addition, the pressure applied by the squeezer according to the invention is substantially constant throughout the entire working stroke compared with the gradual pressure application from an initial low value to the final pressure in case of devices employing linkage or other transmitting mechanism between the piston and anvil or other pressure applicator, as illustrated at a and b in Figure 10, respectively, representing the plots of the working pressure during the piston stroke obtained by the invention and with the known constructions, respectively.

While I have shown and described a few desirable embodiments of the invention, it is un-

derstood that this disclosure is for the purpose of illustration and that various changes in shape, proportion and arrangement of parts as well as the substitution of equivalent elements for those herein shown and described may be made without departing from the spirit and scope of the invention as defined in the appended claims.

I claim:

1. In a rivet squeezer, a housing forming a cylinder having a plurality of chambers, a plurality of pistons each movable within one of said chambers, a hollow piston rod extending into all the chambers and projecting from both ends of said cylinder, said piston rod having inlet port means connecting the inside thereof with said chambers on one side of said pistons, a rivet set at one of the projecting ends of said rod, a yoke carrying a cooperating riveting tool and secured to said housing, control means for admitting compressed air or fluid through said rod to said chambers, said control means comprising an adjustable valve member carried by an extension of said housing and cooperating with an inlet opening of and arranged at the opposite projecting end of said rod, and means to resiliently urge both said piston rod and said valve member to a predetermined starting position, whereby to normally interrupt the supply of compressed air or fluid to said chambers and to synchronize in a continual follow-up action the advance and return of said pistons with the adjusting movement of said valve member.
2. In a rivet squeezer, a housing forming a cylinder, at least one piston movable within said cylinder, a hollow piston rod projecting from both ends of said cylinder, said rod having inlet port means connecting the inside thereof with said cylinder on one side of said piston, a rivet set at one of the projecting ends of said rod, a yoke carrying a cooperating riveting tool and secured to said housing, control means for admitting compressed air or fluid through said rod to said cylinder, said control means comprising an adjustable valve member carrier by an extension of said housing and cooperating with an inlet opening of and arranged at the opposite end of said rod, and means to resiliently urge both said piston rod and said valve member to a predetermined starting position, whereby to normally interrupt the supply of compressed air or fluid to said cylinder and to synchronize in a continual follow-up action the advance and return of said piston with the adjusting movement of said valve member.
3. In a rivet squeezer, a housing forming a cylinder, at least one piston movable within said cylinder, a hollow piston rod projecting from both ends of said cylinder, said rod having inlet port means connecting the inside thereof with said cylinder on one side of said piston, a rivet set at one of the projecting ends of said rod, a plug in said rod adjacent to said rivet set, means securing said plug to said housing while allowing axial movement of said rod a yoke carrying a cooperating riveting tool and secured to said cylinder, control means for admitting compressed air or fluid through said rod to said cylinder, said control means comprising an adjustable valve member carried by an extension of said housing and cooperating with an inlet opening of and arranged at the opposite projecting end of said rod, and means to resiliently urge both said piston rod and said valve member to a predetermined starting position, whereby to normally interrupt the supply of compressed air or fluid to said cylinder and to synchronize in a continual follow-up action the advance and return of said piston with the adjusting movement of said valve member.
